COMPARTMENTED TRAY

Stephen Lipka, Melbourne, Fla.

Application November 21, 1957, Serial No. 48,594

Term of patent 14 years

(Cl. D44—10)

Fig. 1.

Fig. 2.

Fig. 3.

Fig. 4.

Fig. 5.

Fig. 6.

Figure 1 is a plan view of a compartmented tray showing my new design;

Figure 2 is a side elevation thereof;

Figure 3 is an opposite side elevation thereof;

Figure 4 is a front end elevation thereof;

Figure 5 is a rear end elevation thereof; and

Figure 6 is a longitudinal section taken on line 6—6 of Figure 1.

I claim:

The ornamental design for a compartmented tray, as shown.
